(57) **CLAIM**

The ornamental design for a foldable electric kettle, as shown and described.

DESCRIPTION

FIG. 1 is a top, front, right perspective view of a foldable electric kettle showing my new design;

FIG. 2 is a bottom, rear, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded top, front, right perspective view of the foldable electric kettle of FIG. 1; and,

FIG. 10 is a top, front, right perspective view of the foldable electric kettle of FIG. 1 where the foldable electric kettle is in a folded state.

The broken lines in the drawings depict portions of the foldable electric kettle that form no part of the claimed design.

1 Claim, 10 Drawing Sheets
